UNITED STATES PATENT OFFICE.

EDMOND A. MACBETH, OF HOLLYWOOD, FLORIDA.

SAFETY HIGHWAY APPROACH TO RAILWAY CROSSINGS.

Application filed July 15, 1926. Serial No. 122,609.

This invention is a novel improvement in safety highway approaches to railroad crossings, and the principal object of the invention is to provide means for preventing accidents to vehicles at railroad crossings, by compelling the operator to retard the speed of the vehicle before reaching such crossings, and to compel the driver to observe the crossing signal at a distance from the track and hence realize the proximity of the crossing before it would be too late to slow down or stop.

A further object of the invention is to provide means for so positioning the vehicle on the highway that the driver in one position will get a clear view down the track, and in another position a clear view up the track, thereby reducing the possibility of accident caused by the rapid approach of an unseen train.

Other minor objects of the invention will be hereinafter set forth.

It is generally conceded that a vast majority of grade crossing accidents are caused by the failure of the driver of a vehicle to think. Usually their minds are on subjects other than the railroad track or the danger of approaching trains. Signs placed at the sides of the highway are constantly overlooked or not read. The fact that my invention not only displays warning to the driver but compels him to do a physical act aside from the regular routine of driving, i. e., slow down and turn at an angle, before he reaches the track, is sufficient to forcibly remind the driver that he is about to cross a railroad and hence being forewarned he will instinctively look for approaching trains.

I will explain the invention with reference to the accompanying drawing which illustrates one practical embodiment thereof to enable others to adopt and use the same, and will summarize in the claims the novel features of construction, and the novel combination of parts, for which protection is desired.

In said drawings:—

Fig. 1 is a diagrammatical plan view of a railway crossing showing my novel safety crossing signals and obstructions applied to the highway.

Fig. 2 is an elevation of the signal.

As shown in the drawings, A designates a public highway of usual width, and B designates a railroad track, crossing said

highway. Disposed some 40 feet, more or less, from the railroad track B, in the middle of the highway A, and on each side of track B, are a pair of parallel obstructions 60 1, 1^a, which are preferably disposed transversely of the highway, and preferably spaced a few feet apart, the obstructions 1, 1^a, being preferably about four feet in length. Obstructions 1, 1^a, are preferably 65 made of stone or concrete, similar to the usual curbing and are sufficiently high to compel vehicles to drive around same, the obstructions restricting the effective width of the highway at such points.

Diverging from the inner members 1^a of each pair of obstructions 1, 1^a, are symmetrically disposed lateral obstructions 2, extending from points substantially opposite each end of obstructions 1^a to the sides of the 75 highway A, said obstructions 2 diverging towards the track B, as shown, and sufficient space being left between the adjacent ends of obstructions 1^a and the obstructions 2, to permit a single vehicle to pass therebetween on each side of the obstructions 1^a towards and from the track B.

Hence, obstructions 1, 1^a, 2, and 3 are so placed in the highway as to materially reduce the effective width of the highway at 80 such points, compelling the vehicle to follow substantially semi-circular paths (indicated in Fig. 1 in dotted lines,) on each side of the obstructions 1, 1^a, in passing towards or from the track B.

In the center of each obstruction 1, 1^a, is mounted a visual signal, preferably comprising a metallic sign 4, as shown in Fig. 2, said sign being preferably rectangular in shape and mounted on a suitable base 90 embedded in the members 1, 1^a. Sign 4 is preferably enamel coated, and provided with a removable frame in which advertising matter may be inserted. Above the frame 4 are luminous signs 4^a, 4^b and 4^c, preferably 95 rectangular in shape, placed one above the other. The top sign 4^a preferably bears the legend "D*A*N*G*E*R"; the middle sign 4^b bears the legend "Railroad crossing"; and the lower sign 4^c, bears the legend "S*T*O*P". 100 The printing on signs 4^a, 4^b and 4^c is preferably made with luminous paints whereby at night the headlights of approaching vehicles will properly illuminate the signs; also, suitable reflectors may be used to facilitate the illumination of said signs.

In operation, as a vehicle approaches the

track B on the highway, the obstructions 3, 3, will narrow the effective width of the roadway A, compelling the driver to slow down to a sufficiently slow speed to pass in 5 a semicircular path around the obstructions 1, 1^a, as shown in dotted lines in Fig. 1. At the same time, the headlights of the approaching vehicle will illuminate the danger signs 4^a, 4^b, and 4^c and warn the operator to 10 reduce the speed of the vehicle.

Members 1, 2, and 3 should be so positioned that vehicles must slow down to a speed of not more than ten miles an hour, so that after the obstructions are passed, 15 there is ample time for the driver to bring the vehicle to a stop before reaching the track.

While the vehicle is passing between obstructions 1 and 3, the vehicle will be turned 20 on the road so that the driver will have a clear and unobstructed vision down the track in one direction, and when the vehicle passes between obstructions 1^a and 2, the vehicle will be turned on the road in the opposite 25 site direction so that the driver will have a clear and unobstructed view down the track B in the opposite direction.

My signals and obstructions may be constructed at low cost, and may be readily 20 erected by unskilled workmen. I do not consider my invention limited to the exact forms shown in the drawing, for obviously changes may be made therein within the scope of the 25 claims.

35 I claim:—

1. A safety highway approach to railway crossings, comprising a transversely disposed obstruction in the highway restricting the normal width of the highway; a pair of 40 symmetrically disposed lateral obstructions in front of and converging towards said first mentioned obstruction from opposite sides of the highway; and a second pair of symmetrically disposed lateral obstructions behind and converging towards 45 said first mentioned obstruction from opposite sides of the highway; the distance between said obstructions being sufficient to permit a single vehicle to pass around each side of the first mentioned 50 obstruction.

2. A safety highway approach to railway crossings, comprising a pair of parallel transversely disposed obstructions in the highway restricting the normal width of the 55 highway; a pair of symmetrically disposed lateral obstructions in front of and converging towards said parallel obstructions from opposite sides of the highway; and a second pair of symmetrically disposed lateral obstructions behind and converging towards 60

said parallel obstructions from opposite sides of the highway; the distance between said obstructions being sufficient to permit a single vehicle to pass around each side of the parallel obstructions. 65

3. A safety highway approach to railway crossings, comprising a pair of parallel transversely disposed obstructions in the highway restricting the normal width of the highway, visual signals on each of said obstructions; a pair of symmetrically disposed lateral obstructions in front of and converging towards said parallel obstructions from opposite sides of the highway; and a second pair of symmetrically disposed lateral obstructions behind and converging towards 70 said parallel obstructions from opposite sides of the highway; the distance between said obstructions being sufficient to permit a single vehicle to pass around each side of the parallel obstructions. 75

4. A safety highway approach to railway crossings, comprising a pair of parallel transversely disposed obstructions in the highway on each side of the crossing, restricting the normal width of the highway, visual signals on each of said obstructions; pairs of symmetrically disposed lateral obstructions in front of and converging towards each pair of parallel obstructions, 85 from opposite sides of the highway; and pairs of symmetrically disposed lateral obstructions behind and converging towards each pair of parallel obstructions from opposite sides of the highway; the distance between said obstructions being sufficient to permit a single vehicle to pass around each side of the 90 parallel obstructions. 95

5. A safety highway approach to railway crossings, comprising a pair of parallel transversely disposed obstructions in the highway on each side of the crossing, restricting the normal width of the highway; visual signals on each of said obstructions; pairs of symmetrically disposed lateral obstructions in front of and converging towards each pair of parallel obstructions, 100 from opposite sides of the highway; and pairs of symmetrically disposed lateral obstructions behind and converging towards each pair of parallel obstructions from opposite sides of the highway; the distance between adjacent ends of the said obstructions being sufficient to permit a single vehicle to 105 pass in a semi-circular path around the sides of each pair of parallel obstructions. 110

In testimony that I claim the foregoing as my own, I affix my signature.

EDMOND A. MACBETH.
